UNITED STATES PATENT OFFICE.

EDWIN FITCH NORTHRUP, OF PRINCETON, NEW JERSEY, ASSIGNOR, BY MESNE ASSIGNMENTS, TO AJAX ELECTROTHERMIC CORPORATION, OF TRENTON, NEW JERSEY, A CORPORATION OF NEW JERSEY.

METHOD AND APPARATUS FOR MELTING OXIDS, &c., WITHOUT CONTAMINATION.

1,378,189.

Specification of Letters Patent. Patented May 17, 1921.

Application filed July 30, 1919. Serial No. 314,241.

To all whom it may concern:

Be it known that I, EDWIN F. NORTHRUP, a citizen of the United States, residing at 30 Wiggins street, Princeton, in the county 5 of Mercer and State of New Jersey, have invented a certain new and useful Method and Apparatus for Melting Oxids, &c., without Contamination, of which the following is a specification.

10 My invention relates to electric furnaces and allied apparatus and appliances used in high temperature melting and heat treatment.

15 The purpose of my invention is to provide for melting metallic oxids or other materials subject to contamination in such a manner as to prevent contact with any contaminating material during the melting.

20 A further purpose is to form a carbid coating upon the surface of a graphite crucible by union at high temperature between the graphite upon the crucible surface and a metal yielding coating.

25 A further purpose is to melt a metallic oxid floated upon the surface of a molten pool of metal, preferably its own metal, by heat generated in the pool in the oxid or in the container.

30 A further purpose is to form a protective side wall coating for a lighter content being melted or heat-treated, by spreading a liquid (here molten) content about the side wall by centrifugal action.

35 A further purpose is to melt down a furnace content as a continuing operation, feeding the material in at the top, heating it there by electrically induced current, concentrating the current in the lower part, preferably by reducing the cross section 40 there of the material within which the heat is developed or to which it is applied, and passing the molten material through as it becomes melted, at all times protecting from contamination of the material by the surfaces with which it engages.

45 Further purposes will appear in the specification and in the claims.

50 My invention relates to the methods disclosed and to apparatus by which the processes may be carried out.

I have preferred to illustrate my inven-

tion by a few only of the forms in which it may appear, selecting different forms to illustrate different applications of my invention without attempting completeness of 55 illustration and recognizing that many other varieties of my invention may be designed readily with the information contained herein.

Figures 1 and 2 are vertical longitudinal 60 sections of a crucible embodying one form of my invention.

Figs. 3, 4 and 5 are central vertical sections illustrating three other constructions by which my invention can be carried out. 65

Similar numerals indicate like parts throughout the specification.

In the use of induction electric furnaces, particularly of the type invented by me and shown in my Patents Nos. 1,286,394 and 70 1,286,395 of December 3, 1918, and No. 1,297,393 of March 18, 1919, and in various applications copending herewith, utilizing high frequency current to induce heating current in the resistor, it is frequently desirable to melt a material in a crucible or other container which injuriously affects the contents. The latter, for example, may be a metallic oxid which is a non-conductor of 75 electricity and has a high melting point. 80 In such a case an electrically conducting crucible is used.

However, the higher the temperature to be attained the fewer the materials of any character which are available for crucible 85 use. Graphite, the best electrically-conducting crucible materials at any electric furnace temperature and particularly suitable for very high temperatures and for the larger crucibles, has a reducing action upon 90 the oxids. Other materials, susceptible to contamination by the crucible for whatever reason, require protection from contact with it.

My present invention is directed to the 95 methods and means for handling materials to be melted while protecting from contaminating influences.

Because the melting of oxids has presented great difficulty on account of the 100 high temperature usually required and these oxids, most conveniently melted in graphite

crucibles, when melted by existing commercial methods have been changed by reduction to their metals through the action of carbon upon them, I have selected for my first illustration, (Figs. 1 and 2) a method and graphite crucible protecting the contents from contamination.

The graphite crucible 7 is painted or otherwise covered with an oxid of a metal 10 whose carbid it is desired to form upon the face coated. I have shown the coating as internal only as it will ordinarily not be necessary to coat the outside; but the invention is not so restricted. An oxid which can be 15 used to advantage is that of aluminum which may be painted upon the surface intended to be rendered safe from contamination.

Whatever the material used, after the 20 surface has been covered with a layer of this material as at 8 the crucible is heated to a high temperature, preferably by a high frequency induction coil, of which examples are shown in my patents above and of which 25 the best form is seen in my Patent No. 1,328,336 issued January 20, 1920. The oxid coating is reduced at the high temperature and the metal thus freed forms a carbid with the graphite of the crucible, as seen at 9.

30 The oxids of aluminum, boron, thorium and magnesium, magesium chlorid and the salts of iridium, osmium and platinum are given by way of suggestion of the variety of initial coatings which may be used and, 35 fused, have no reducing effect upon the melt.

Any of these and other materials, within 40 the easy selection of the chemist in view of my disclosure, form upon the walls of the graphite container a coherent, intimate, strong coating of carbid merging into the 45 graphite and capable of withstanding a very high temperature. With other crucibles intended to have their contents protected against different kinds of contamination other forms of coating could be used.

This supplies a trustworthy crucible capable of general high temperature use but particularly suited for use in connection with a high frequency electric induction furnace 50 (because it is a conductor of electricity) and in which the lining is chemically united with the container and not a mere coating thereon.

Taking up next the form of the invention 55 shown in Fig. 3, I form a crucible out of a molded oxid 10, such as the oxid of thorium, titanium, vanadium or zirconium, having a melting point in excess of that of the melt 60 11, here for convenience referred to as an oxid. The oxid 11 is preferably melted by means of a high frequency, artificially cooled, inductor system such as is shown in my application for patent for artificially-cooled high frequency coil, Serial No. 291,161, filed April 18, 1919, using water-cooled coil 12 65 about a supporting quartz tube 13 resting

upon a base 15. The oxid 11 is more readily melted when rested upon a molten pool 14 of its own metal.

In the form shown in Fig. 4 an artificially cooled coil 12' is also shown, mounted about 70 a quartz cylinder but may be free from it to permit rotation of the cylinder and of its base 15'. It is immaterial, so far as the theory of the invention is concerned, whether the coil turns or not, but a stationary coil 75 is more convenient and simplifies connections.

Within the cylinder is shown a refractory heat insulator 16, surrounding a preferably molded non-conducting refractory 17 open 80 at the center at the top and 18 and having the opening relatively enlarged or counterbored to provide a cavity 19 within which the melting is to take place.

In order to protect the material to be 85 melted, here exemplified as an oxid 11', from contamination by the walls of the refractory 17 I provide a protective coating 20 of molten metal which will not contaminate, (ordinarily the same metal as that in the oxid) 90 and spread it over the walls of the cavity by centrifugal action by mounting the base 15' upon a shaft 21 in fixed bearings 22 and rotating the shaft, base and supported parts by pulley 23 and belt 24. Some one of the 95 parts within the refractory 16 must be electrically conducting. This may be the molten metal, the oxid to be melted or even the refractory 17.

The metal may be spread over the surface 100 of the cavity before the oxid is inserted, or may be relied upon to take and maintain this position afterward in view of its greater specific gravity than that of the oxid. Where the molten metal is not that whose oxid is 105 being melted it should have a higher boiling point than the boiling point of the oxid.

In Fig. 5 a continuously operative form is shown in which an outer cylinder 13', which may be quartz, is given different diameters 110 at 25 and 26 to receive artificially cooled high frequency coils 12', 12''. These may be energized by the same high frequency single phase supply or, conveniently by different phases of the same supply. For different 115 connections by which the single phase and two phase high frequency current may be produced and applied reference is made to my patents and applications above mentioned.

A very thin funnel-shaped crucible 27 of a high fusing metal such as iridium or of graphite—which in that case would be prepared by a carbid lining—is heat-insulated from the cylinder, as by purest zirconia sand 125 28, and receives a continuous supply of unfused oxid from a hopper 29. The induced current heats the oxid to a high temperature and, with the greater concentration within the smaller cross section at the bottom 130

- (neck) of the crucible it may be adjusted to fuse the oxid there and not fuse that in the upper part of the crucible; providing for a continuous progression of the oxid downwardly and the delivery of molten oxid free from contamination in a continuous stream through an opening 30' in a support 30 into a crucible 31 of molded oxid. 5
- The induced current may be further intensified in the lower part of the crucible by increasing the turns of the coil or by other means pointed out by me in my patents and application. 10
- In all of these forms the oxid or other material is melted in a special crucible or one having a specially prepared lining free from contaminating effect upon the oxid and preferably by a current induced in the oxid or in the crucible. 15
- Having thus described by invention, what I claim as new and desire to secure by Letters Patent is:—
1. In the melting of metallic oxids and like chemicals the combination of a crucible composed of a metallic oxid having a melting point in excess of the intended temperature of the melt and a molten body of the metal whose oxid is being treated within the bottom of the crucible. 25
  2. In the melting of metallic oxids and like chemicals, the combination of a crucible composed of a metallic oxid having a melting point in excess of the intended temperature of the melt and a body of the metal whose oxid is being treated, within the crucible. 30
  3. A molded crucible for melting oxids, etc., formed of a high melting oxid in combination with a lower melting oxid content therefor and a molten body of the metal whose oxid is being melted in contact with the oxid content. 40
  4. In an electric furnace for melting oxids, etc., without reduction a crucible free from reducing action upon its content and having a high melting point and a molten pool therein of the same metal as that of the oxid. 45
  5. A crucible comprising a molded metallic oxid having a high melting point in combination with a coil surrounding the crucible, a high frequency source of current and connections for applying the current to the coil. 50
  6. In an electric furnace for melting oxids, etc., a non-reducing crucible, an electrically conducting pool therein having a melting point as high as that of the oxid, a source of high frequency electric current and connections for applying the current inductively about the pool. 55
  7. In an electric furnace, an inductor coil, a support therefor, a source of high frequency current, connections for applying the current to the coil, a crucible within the
  - support, comprising a metallic oxid of higher melting point than the material intended to be melted therein and a fluid resistor in the crucible of higher melting point and specific gravity than the intended melt. 70
  8. A crucible of electrically conducting material in combination with a carbid coating for said crucible.
  9. A graphite crucible in combination with a carbid lining intimately associated therewith. 75
  10. A crucible in combination with a carbid lining merging thereinto and chemically formed thereon.
  11. A crucible of electrically conducting material having a lining intimately connected with it comprising a carbid of the material of the crucible. 80
  12. A crucible having a carbid lining blending into the material of the crucible. 85
  13. A graphite crucible in combination with a non-silicious, non-reducing lining rigidly connected therewith.
  14. An electric furnace comprising an inductor coil, a source of high frequency current, connections for applying the current to the coil, a rotatable crucible within the coil and means for rotating the crucible while it is being acted upon by the coil. 90
  15. An electric furnace comprising a stationary inductor coil, connections for applying the current to the coil, a rotatable crucible within the coil and means for rotating the crucible while it is being acted upon by the coil. 95
  16. An electric furnace comprising an inductor coil, a source of high frequency current, connections for applying the current to the coil, a rotatable crucible within the coil having an enlarged central bore and means for rotating the crucible while it is being acted upon by the coil. 100
  17. An electric furnace comprising an inductor coil, a source of high frequency current, connections for applying the current to the coil, a rotatable crucible within the field of the coil and having an enlarged bore and means for rotating the crucible while it is being acted upon by the coil. 110
  18. An electric furnace comprising an inductor coil, a source of high frequency current, connections for applying the current to the coil, a rotatable crucible within the coil of nonreducing material, means for rotating the crucible while it is being acted upon by the coil and a molten nonreducing charge therein different from the melt. 115
  19. An electric furnace comprising a crucible having tapering cross section smaller at the bottom in combination with a high frequency inductor surrounding the crucible and concentrating inductive effect more greatly upon the lower portion than upon the upper portion. 125
  20. An induction furnace, comprising 130

upper and lower communicating tapering furnace sections in combination with separate inductor coils therefor and electric current supply of different phase for the two 5 coils.

21. An electric furnace for melting oxids free from reduction, comprising a generally tapered crucible of nonreducing material, continuously open at the bottom in combination with high frequency inductor coil heating means therefor, having greater concentration at the bottom.

22. In an electric furnace for melting oxids free from reduction, a thin furnace lining of high fusing point metal, a casing surrounding the same, finely divided refractory material between the casing and the lining, supporting the lining, an inductor coil surrounding the casing and high frequency current supply for the coil.

23. The method of forming a lining for a crucible, which consists in coating the crucible with a metallic compound capable of reduction by heat, such as an oxid of aluminum or a chlorid of a metal of the platinum group, and heating it to a high temperature to cause reduction of the metallic compound and combination of the metal therefrom with the material of the crucible.

24. The method of protecting a melt from contamination from a graphite crucible, which consists in coating the crucible with a reducible metallic oxid or chlorid and in heating the crucible to cause reduction of the coating and combination of the metal thus freed with the graphite of the crucible.

25. The method of lining a crucible having a reducing action upon the material contained, to protect against this reducing action, which consists in coating the crucible with a material capable of being reduced by the reducing action of the crucible and of chemically combining with the crucible when so reduced and subsequently heating 45 the crucible so coated to bring about the reduction and recombination.

26. The method of lining a crucible composed of material deleterious to certain intended contents, which consists in utilizing 50 the deleterious characteristic of the crucible to transform a lining thereto so that it shall recombine with the material of the crucible to protect against further deleterious action.

27. In the protection against contamination of the content of the crucible of electric furnaces upon substance within the crucible, the process, which consists in coating the crucible with a material subject to the same character of contamination and heating the 60 crucible to cause the contaminating action of

the crucible upon the lining to change the character of the lining, and, as this lining is changed to recombine with the crucible.

28. The method of melting a metallic oxid free from reduction, which consists in 65 melting it by high frequency induction within a crucible having walls composed of a metallic oxid of higher melting point than the oxid being melted in the presence of a molten body of the metal of the oxid to be 70 melted.

29. The method of melting an oxid free from reduction, which consists in melting the oxid in a nonreducing crucible in the presence of the metal of which it is an oxid 75 by current induced in the oxid or the metal beneath it.

30. The method of protecting a material being treated from contact with the walls of the vessel in which the treatment is taking place, which consists in providing a liquid or molten content within the vessel, which content is heavier than the material being treated and in whirling the vessel during the treatment to spread the heavier 85 content between the material treated and the walls of the vessel while the treatment is taking place.

31. The method of protecting an oxid from contamination by contact with the crucible within which it is being melted which 90 consists in providing a pool of molten metal beneath the oxid in the crucible and whirling the crucible while the oxid is being melted to distribute the metal about the 95 walls of the crucible.

32. The method of protecting an oxid from contamination by contact with the crucible within which it is being melted which 100 consists in providing a pool of molten metal like that of the oxid beneath the oxid in the crucible and whirling the crucible while the oxid is being melted to distribute the metal about the walls of the crucible.

33. The method of protecting an oxid 105 from contamination by contact with the crucible within which it is being melted which consists in maintaining a layer of protective molten metal between the oxid and the wall of the crucible.

34. The method of protecting an oxid from reduction while melting it, which consists in constantly progressing the oxid from a region of relatively large cross section and low temperature through regions of small 115 cross section and high temperature until the oxid is molten and draining the oxid as it is melted into a mold while maintaining the oxid in contact with nonreducing surfaces.

EDWIN FITCH NORTHRUP.
